UNITED STATES PATENT OFFICE.

JOHN F. HAVEMEYER, OF ARDSLEY-ON-HUDSON, NEW YORK.

INSERT FOR CONCRETE CONSTRUCTION.

Application filed February 24, 1922. Serial No. 538,880.

To all whom it may concern:

Be it known that I, JOHN F. HAVEMEYER, a citizen of the United States, and a resident of Ardsley-on-Hudson, county of Westchester, State of New York, have invented an Improvement in Inserts for Concrete Construction, of which the following is a specification.

The present invention relates to concrete construction and more particularly to attachment sockets for securing lath, facings and the like to concrete structures. The object of the invention is to provide an improved attachment device for this purpose.

15 Metal lath and the like are customarily secured to concrete structures by securing means which is affixed to the forms in such manner that a part will be embedded in the concrete when poured and a part will 20 project sufficiently to provide for attachment or by making holes in the concrete and introducing expansion bolts into the holes.

25 One method of providing attachment which affords certain advantages is to insert 30 nails with or without anchoring devices in such position that when the concrete is poured the head of the nail will be embedded in the concrete and the point will project to be bent over the lath or other attached facing for securing the same. If the nails are 35 driven into the forms a sufficient distance to afford the necessary projection when the forms are removed, the removal of the forms is rendered difficult and the forms are 40 likely to be split during removal. If, as is frequently done, holes are drilled to receive the nails, the work of drilling the holes involves considerable labor and expense.

The present invention provides a device 45 which can be easily applied to forms and one permitting easy removal of the forms when the concrete has set.

The invention will be best understood 50 from a description of an illustrative embodiment thereof, reference being made to the accompanying drawings, forming a part hereof, in which

55 Figure 1 is a sectional view of a concrete structure showing a fastening device embodying the principles of the invention in the position in which it is held during the pouring of the concrete.

60 Figure 2 is a similar sectional view showing the relation of parts after the forms are

removed and a facing applied and secured in place by means of the device.

The device shown for the purposes of illustrating the invention has an attachment socket 5 adapted to be embedded in the concrete and designed to afford support for a tie member 6, to which the lath or other attached parts may be secured. The tie member is so arranged as to be capable of a limited vertical movement whereby a minimum projection may be afforded for securing to the form and a maximum projection may be provided after the concrete has set for attachment of lath or the like by drawing out the tie member. By this arrangement the tie member may be inserted into the form a sufficient distance to provide a support for the socket member on the form during the pouring of the concrete without, however, providing such secure attachment as would prevent the easy removal of the forms from the concrete when set.

The socket member or insert and the tie member are so constructed that the concrete when poured will not form a lock to prevent pulling out of the tie member to its outermost operative position. As shown, the socket member has an opening 7 at the top, which the head 8 of the tie member is adapted to close, thereby preventing concrete entering the socket member. The lower opening through which the attaching end of the tie member projects is restricted to prevent the passing of the head, thereby providing means for limiting the downward movement of the tie member. A nail somewhat longer than the socket member may form a cheap and effective tie member and one which may easily be obtained, leaving only the socket member to be specially manufactured.

The socket member shown may be cheaply manufactured by forming it of a wire coil shaped to present an upper preferably cylindrical portion 10 of a size such that the head of the nail will sufficiently close its upper end to prevent the concrete flowing into the socket member, and a lower preferably cylindrical portion 11 of such length as to hold the head of the nail a sufficient distance into the concrete in its final position. The portion 12 connecting the larger upper section and the lower smaller section may be tapered as shown to permit the head

of the nail to, in a measure, wedge therein, an action which is facilitated by the coil structure. The tapered section also forms a lock in the concrete at a point adjacent the head of the nail where it is most needed and at a sufficient distance from the surface of the concrete. The lower section of the socket member serves also to increase the lateral bearing area adjacent the surface of the concrete as compared with an arrangement in which the bare nail engaged the concrete so that when the nail is bent laterally in securing a facing thereto there is less likelihood of the concrete being chipped. The lower section is preferably of substantial length for the reason also that it is desirable to hold the upper end of the nail rigid while bending the lower end about a facing to be secured.

20 In use the nail is inserted through the socket member and driven into the form to secure both the nail and socket member in the position which it is to take in the concrete. The socket member forms a stop to determine the distance which the nail is driven into the form. When the concrete is set, the forms are pulled off. The grip of the forms on the nails is sufficient to draw them outward to their outermost position.

25 If, for any reason, a nail fails to draw out, it can later be pulled out by means of a hammer or other suitable tool. The lath is then applied and the nail is bent laterally around a portion of the lath. There is a tendency for the head of the nail to be wedged between two portions of wire by the action of bending the nail. Ordinarily the joint between the head of the nail or other tie member and the upper edge of the socket member is tight enough to prevent any inflow of the concrete mixture, making it unnecessary to provide an effective closure.

The words "upper" and "lower" refer to the relative position of parts in the drawing, which illustrates a ceiling lath secured to overhead concrete, the words being used merely for convenience of description and not as words of limitation.

Various possible embodiments may be made of the invention and various changes in the embodiment described may be made, all within the scope of the subjoined claims.

What I claim is:

1. As an article of manufacture, an insert for concrete construction adapted to be embedded within the concrete consisting of a closely-wound wire spiral formed to present an upper section of relatively large diameter and a lower section of relatively small diameter.
2. As an article of manufacture, an insert for concrete construction adapted to be embedded within the concrete consisting of a closely wound wire spiral formed to present an upper section of relatively large diameter and a lower section of relatively small diameter.
3. An attaching device for concrete construction comprising a socket having an opening at the top and a tubular portion at the bottom, together with a tie member adapted to afford attachment vertically movable in said socket, said tie member being arranged when in its upper position to close the opening at the top and to project at the bottom a sufficient distance to permit securing to a form, and when in its lower position to project a greater distance to afford attachment for an article.
4. An attaching device for concrete construction comprising a socket having an opening at the top and a tubular portion at the bottom, together with a tie member vertically movable in said socket, having a head larger than the interior of said bottom tubular portion arranged when in its upper position to close the opening at the top of the socket.
5. As an article of manufacture, an attachment for concrete construction comprising a socket member having a restricted opening at its lower end, a tie member vertically movable through said restricted opening and having an integral head within the socket member larger than said restricted opening.
6. An attachment for concrete construction comprising a socket member having a tubular shank at its lower end, a tie member vertically movable through said shank and having a head larger than the opening bore of said shank, whereby downward movement of the tie member is limited, the lower end of said tie member when in its uppermost position projecting from the lower end of the socket a sufficient distance to permit it to be secured to a form.
7. An attaching device for concrete construction comprising a tie member having a head, a tubular member shorter than said tie member in which the tie member is longitudinally movable, having a larger upper portion with an opening at the top of substantially the size of the head of the tie member and a lower portion smaller than the head and an intermediate tapered portion in which the head wedges.
8. An attaching device for concrete construction comprising a tie member, having a head, a tubular member shorter than said tie member in which the tie member is longitudinally movable, having a larger upper portion with an opening at the top of substantially the size of the head of the tie member, a lower portion smaller than the head, and an intermediate tapered portion in which the head is adapted to wedge.
9. An attaching device for concrete construction comprising a tie member having

10 a lower section of relatively small diameter, and an intermediate tapered section.

11 3. An attaching device for concrete construction comprising a socket having an opening at the top and a tubular portion at the bottom, together with a tie member adapted to afford attachment vertically movable in said socket, said tie member being arranged when in its upper position to close the opening at the top and to project at the bottom a sufficient distance to permit securing to a form, and when in its lower position to project a greater distance to afford attachment for an article.

12 4. An attaching device for concrete construction comprising a socket having an opening at the top and a tubular portion at the bottom, together with a tie member vertically movable in said socket, having a head larger than the interior of said bottom tubular portion arranged when in its upper position to close the opening at the top of the socket.

13 5. As an article of manufacture, an attachment for concrete construction comprising a socket member having a restricted opening at its lower end, a tie member vertically movable through said restricted opening and having an integral head within the socket member larger than said restricted opening.

14 6. An attachment for concrete construction comprising a socket member having a tubular shank at its lower end, a tie member vertically movable through said shank and having a head larger than the opening bore of said shank, whereby downward movement of the tie member is limited, the lower end of said tie member when in its uppermost position projecting from the lower end of the socket a sufficient distance to permit it to be secured to a form.

15 7. An attaching device for concrete construction comprising a tie member having a head, a tubular member shorter than said tie member in which the tie member is longitudinally movable, having a larger upper portion with an opening at the top of substantially the size of the head of the tie member and a lower portion smaller than the head and an intermediate tapered portion in which the head wedges.

16 8. An attaching device for concrete construction comprising a tie member, having a head, a tubular member shorter than said tie member in which the tie member is longitudinally movable, having a larger upper portion with an opening at the top of substantially the size of the head of the tie member, a lower portion smaller than the head, and an intermediate tapered portion in which the head is adapted to wedge.

17 9. An attaching device for concrete construction comprising a tie member having

- a head, a tubular member shorter than said tie member in which the tie member is longitudinally movable adapted to be substantially closed by the head of the tie member 5 and a lower portion having a bore smaller than the head to limit the downward movement of the tie member.
10. An attaching device for concrete construction comprising a tie member, a tubular member in which the tie member is longitudinally movable having a larger upper portion with an opening at the top, the top of the tie member being of a shape and size to substantially close the opening at the top 15 of the tubular member when the tie member is in its upper position, and the tubular member being formed to provide means to limit the downward movement of the tie member.
20. 11. An attaching device for concrete construction comprising a tie member having a head and shank, a tubular member consisting of a closely-wound wire spiral in which the tie member is longitudinally movable, having a larger upper portion to receive the head and a smaller lower portion forming a retaining means for the tie member.
25. 12. An attaching device for concrete construction comprising a nail, a tubular member shorter than said nail open at both ends, in which member the nail is longitudinally movable, the upper open end being of a size to be substantially closed by the nail head, the tubular member being formed to provide 30 means for limiting the downward movement of the nail.
35. 13. An attachment socket for concrete construction of tubular form open at both ends, having a larger upper cylindrical portion adapted to receive and substantially fit the head of a nail inserted therein, and a smaller lower cylindrical portion coaxial therewith adapted to receive the shank of the nail.
40. 14. An attachment socket for concrete construction of tubular form open at both ends, having a larger upper cylindrical portion adapted to receive and substantially fit the head of a nail inserted therein, a smaller lower cylindrical portion coaxial therewith adapted to receive the shank of the nail and an intermediate tapered portion in which the head of the nail is adapted to be drawn and wedged.
45. 15. An attachment socket for concrete construction of tubular form open at both ends, having a larger upper cylindrical portion adapted to receive and substantially fit the head of the nail, and a smaller lower portion adapted to engage the head of the nail to 50 form a stop preventing withdrawal of the nail therethrough, the distance from the upper end to the lower end being somewhat less than the length of the nail.
55. 16. An attaching device for concrete construction comprising a casing, a tie member 55 of a length greater than that of the casing and longitudinally movable therein, the casing and tie member having interengaging parts to limit the outward movement of the tie member, the length of the tie member and the possible relative movement being such that when the tie member is in its relatively retracted position, its projecting end may be inserted in a form to provide a support for holding the casing in predetermined 70 position relative to the tie member and the form while the concrete is being poured therearound, said tie member being longitudinally movable in the casing in such manner that after the hardening of the concrete 75 and removal of the form, the tie member can be withdrawn to project a greater distance from the casing to afford attachment for securing facings.
80. 17. An attaching device for concrete construction comprising a casing, a tie member having a limited longitudinal movement within the casing to project a relatively short distance therefrom or a relatively greater distance therefrom, the interengaging parts 85 of the casing and tie member being so formed that when said tie member is positioned to project a relatively short distance from the casing its projecting end may be inserted in a form to hold the casing in predetermined relation to the form during 90 the pouring of concrete therearound and when, after setting of the concrete and removal of the form, the tie member may be pulled out to project a greater distance from 95 the casing to afford attachment.
100. 18. An attaching device for concrete construction comprising a casing having an opening at the bottom, and a tie member of a length greater than that of the casing and longitudinally movable therein having an integral head larger than the opening, the casing and tie member having opposed shoulders to limit the outward movement of the tie member, the lengths of the tie member and casing and the relative movement being such that when the tie member is in 105 relatively retracted position it projects a relatively short distance from the casing and the interengaging portions of the tie member and casing being so shaped that the casing is held laterally in relatively fixed position relative to the tie member.
110. 19. An attaching device for concrete construction comprising a casing having an opening at the bottom, and a tie member having an integral head larger than the opening, and having a limited longitudinal movement within the casing to project a relatively short distance therefrom or a relatively greater distance therefrom, the interengaging parts of the casing and tie member being so formed that when said tie member is positioned to project a relatively short distance from the casing the casing and tie 115
120. 130. 125.

member are held in relatively fixed position laterally with respect to each other, whereby when the projecting end is supported in fixed position the tie member is also held in substantially fixed position.

20. An attaching device for concrete construction comprising a casing having an opening at the bottom and a tie member having an integral head within the casing larger than the opening, said tie member being movable vertically within the casing and its head so fitting the casing and its shank so

fitting the opening that when the tie member is in its uppermost position the casing and tie member are held in relatively fixed position laterally with respect to each other, whereby when the projecting end is supported in fixed position the tie member is held thereby in substantially fixed position.

In testimony whereof, I have signed my name to this specification this 21st day of February, 1922.

JOHN F. HAVEMEYER.
